INCANDESCENT MANTLE

Harry Rinnman, Berwyn, Ill., assignor to Universal Mantle, Inc., Brookfield, Ill., a corporation of Illinois

Application March 11, 1937; Serial No. 130,382

2 Claims. (Cl. 67—101)

This invention relates to that class of illuminating and gas appliances and accessories grouped under the heading of incandescent mantles, and it has more specific reference to what is believed to be a new and improved base and hanger frame for a conventional net-type mantle.

It is a matter of common knowledge to those skilled in the art to which the invention relates that the so-called conventional inverted bell or hood-type mantle is of such a fabrication as to be comparatively fragile and therefore too delicate to withstand careless handling or adverse flame conditions. I appreciate, of course, that there are many different types of supports and mantles on the market. Thus, in reducing the principles of the present inventive conception to practice, I have been inspired with the feeling that it is nevertheless possible in this already well developed art to provide certain refinements and improvements such as will constitute an advance in the art and trade.

In reducing to practice my conception, I have evolved and produced an arrangement characterized by an expandable and contractible split annulus constituting a base ring and providing an ingenious support and adapter for an inverted U-shaped frame having a suspension hook on which the mantle is detachably supported.

It follows, therefore, that my primary aim is to generally improve upon assemblies of this type by providing an arrangement which is especially adaptable for use in connection with kerosene mantle lamps of the more modern type in use today, this being accomplished through the adoption and use of the adjustable annulus susceptible of being associated with existing equipment on the majority of different lamp constructions, whereby to provide an arrangement having universal characteristics.

Other features and advantages will become more readily apparent from the following description and drawing.

In the drawing:

Figure 1 is an elevational view of an invention embodying the improvements and refinements hereinafter specifically claimed.

Figure 2 is a view at right angles to Figure 1 with portions broken away and shown in section to detail the arrangement for more satisfactory study.

Figure 3 is a top plan view of Figure 1.

Figure 4 is a fragmentary view of the so-called ring-like base unit.

Referring to the drawing, the customary fabricated incandescent hood-type mantle is denoted by the numeral 5 and is provided with a conventional apertured crown having a hanger or loop 6. This is adapted for releasable engagement with a suspension hook 7 on the intermediate or bright portion of the U-shaped frame 8. This frame is adapted for cooperation with the especially constructed self-adapting adjustable base or adapter unit 9, which, in operation, functions as a retaining clamp. This part 9 is adapted to associate itself satisfactorily with different types of variable bases, not shown, already existing in lamp structures. These base members are usually called burner-cones, cone-caps, galleries, mantle frames, burners, circles, rings, etc. Specifically, it comprises a ring or annulus characterized by a scarf-joint 10 of an expandable and contractible slip-type. The ring or annulus is constructed from metal of an appropriate tensile strength and resiliency. The ring 9 as shown in Figure 1 is at nearly its smallest diameter as it will appear in the majority of lamps after installation. As manufactured, flanges 14 and 15 will show a larger open space at the scarf-joint. The sections of scarf-joint formed by ends of flange 11 will overlap at all times. When the ring is compressed to slip inside of another ring, existing in the lamp, the tendency of ring 9 is to expand, thereby producing the necessary clamping action which affixes it firmly in place. On another type of installation wherein the ring is forced to expand slightly to go around the outside of a base member, existing in certain lamps, the tendency is for ring 9 to contract to its original size and this also produces the desired clamping action. In other words, the diameter of ring 9 can be varied slightly by either compressing it to give a smaller diameter or expanding it to furnish a larger diameter. In both cases the ring is so constructed as to tend to return to its original size and that is what furnishes the clamping action which holds it fixed to the means present in the lamp. The part 9 is further characterized by an outstanding central marginal flange 11 having diametrically opposite ears or extinctions 12. The extinctions are in turn formed with bendable malleable terminals 13. These features 13 can be bent up at right angles to the extensions 12 and then wrapped and clenched around the lower ends of the arms of the frame 8 to form receiving and retention sockets therefor, as indicated in Figure 1. This provides a satisfactory assemblage

between the frame and base. The unit 9 may be said to be further characterized by a lower flange, that is, a flange 14 of a true circular type, and an upper flange 15 of an inwardly tapered or conical type. Or stated otherwise, we have in effect a split ring or annulus which by the outwardly extending horizontal flange 11 is divided itself into upper and lower complementary sections or flanges 15 and 14.

Novelty is thought to reside in one instance in the provision of the adjustable adapter unit or annulus 9 characterized by the bendable malleable features 13 susceptible of being transformed into sockets to accommodate the arm portions of the U-shaped frame 8. The essential novelty, however, has to do with the universal aspect of the unit 9 wherein it is susceptible of being operatively associated with different types of mantle supports or burner or mantle fixtures such as are used in present day kerosene lamps. In the ordinary mantles in use on kerosene mantle lamps at present, the entire mantle assembly must be discarded when the mantle is fractured. This necessitates an excessively high retail price for replacement and places an unjust burden on the consumer. The mantle arrangement and frame structure herein described can be inserted into the old frame and effect a considerable saving for the user, since after the adapter structure is put in place, it is only necessary to buy the individual hood mantles.

In connection with the rib or flange 11 forming a part of the unit 9, it is to be stated that this is adaptable as a reinforcing member. It will prevent distortion of the unit from excessive heat or rough handling and tend to keep the entire frame in its original shape. It also supplies some of the spring necessary to give the clamping action to ring 9. It also functions to control the distance between the mantle and the flame, thereby simplifying the installation of this improved universal mantle unit. It is to be noted,

also, that the upper flange 15 slopes inward toward the correspondingly sloped surface of the mantle. The purpose of this angle is to present a larger area of the ring to the mantle, thereby lessening the possibility of breakage.

It is thought that the description taken in connection with the drawing will enable to clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

1. A mantle support of the class described comprising a ring-shaped member formed of metal, with a split in the member providing a scarf joint, an outwardly extending flange on the member and connected therewith at the approximate center thereof, with the circumferentially extending part of the split passing through said flange, an upright mantle supporting frame supported from the flange and supporting a mantle with the lower end thereof in the ring-shaped member.

2. A mantle support of the class described comprising a ring-shaped member formed of metal, with a split in the member providing a scarf joint, an outwardly extending flange on the member and connected therewith at the approximate center thereof, with the circumferentially extending part of the split passing through said flange, an upright mantle supporting frame supported from the flange and supporting a mantle with the lower end thereof in the ring-shaped member, said portion of the ring-shaped member above the flange sloping upwardly and inwardly towards the mantle.

HARRY RINNMAN.
